LOOSE REED FOR LOOMS

Application filed March 14, 1929; Serial No. 347,047.

This invention relates to loose reeds for looms and it is the general object of the invention to provide a simplified connection between a single resilient device or element 5 and a plurality of points along the reed to the end that the reed will yield uniformly.

In certain types of looms, such as silk, for instance, it is customary to provide the reed with a mounting which will permit yielding 10 with respect to the lay. Heretofore the reeds have been held in position by a plurality of springs, one adjacent each of the swords of the lay, and with wide lays several springs have been employed. As a result 15 of this construction it has been very difficult to exert uniform pressure against the reed at different points along its length. It is an important object of my present invention to provide a single, resilient means which is connected 20 at a plurality of spaced points to the reed so that the latter will yield uniformly.

A variety of weights of cloth may be woven on the same loom from time to time, and when changing from one grade to another it is customary 25 to adjust the springs. Where a plurality of springs are employed it is difficult to adjust all of the springs to the same degree of tension, and it also requires considerable time to adjust them. It is a further 30 object of my invention to provide a unitary yielding element operatively connected to the reed at a plurality of points and so mounted that a single adjustment of the unitary device will act to effect a uniform adjustment 35 throughout the length of the reed.

With these and other objects in view which will appear as the description proceeds, my invention resides in the combination and arrangement of parts hereinafter described 40 and set forth in the claims.

In the accompanying drawings, wherein a convenient embodiment of my invention is set forth,

Fig. 1 is a rear elevation of a loom lay having my invention applied thereto;

Fig. 2 is a detailed horizontal section on line 2—2 of Fig. 1 showing the connections to the reed, the lay being indicated in dot and dash lines;

Fig. 3 is a detailed enlarged vertical section on line 3—3 of Fig. 1, and

Fig. 4 is a vertical section on line 4—4 of Fig. 1.

The lay includes a beam L having a lay end 10 at each end thereof, there being in this instance pipe lay swords 11, one for each lay end. The reed R as shown more particularly in Fig. 3 has the lower end thereof received by a groove 12 formed in backstay 13 which extends across the width of the lay. The backstay is braced by an angle iron 14 held to said stay by bolts 15. The ends of the stay and angle iron are attached to brackets 16, there being one bracket on each end of the lay. The upper end of each bracket affords support for a reed cap 17 having a downwardly facing groove 18 which receives the upper edge of the reed R. Each bracket is provided with a gudgeon 19 which extends into a bearing 20 in the adjacent lay end.

It is to be understood that the lay swings around a rocker shaft 21 located in the lower part of the loom and is moved back and forth during normal operation of the loom by mechanism not shown. Ordinarily the brackets 16 and the lay L move without relative motion except when the lay is in extreme forward position when beating in a pick of filling, at which time the backstay 13 may swing around the gudgeons 19 as pivots in order to accommodate any variation in the resistance offered to the reed by reason of unevenness in letting-off of the warp.

The matter thus far described forms no part of my present invention and is customarily employed in conjunction with the previously mentioned sets of springs not shown which are ordinarily mounted on the lay swords and engage the backstay directly.

In carrying my invention into effect I provide a single unitary resilient means and provide connections whereby said means is operatively attached to the reed at a plurality of points along the length thereof. As shown herein I provide a central lay sword 30 which as shown in Fig. 4 is provided with a bracket 31 through which extends a screw eye 32. The bracket is held tightly to the center sword 100.

by means of a clamp 33 held in position by a screw 34. The eye receives the lower hooked end 35 of a tension spring 36. By means of a winged nut 37 mounted on the screw eye and engaging the under side of the bracket I may vary the vertical position of said eye and therefore the tension of the spring.

The upper end of the spring is attached by means of a connector 38 to a flexible strand or cable 39 which acts as an equalizer. The lay is provided with a pair of sheaves 40 and 41, freely rotatable on stud 42, fixed in the top 43 of the central sword 30. One portion of the equalizing cable 39 extends around sheave 40 and to the left as at 44 in Fig. 2, while the other end extends around sheave 41 and to the right as at 45 in Fig. 2. The connector 38 has spaced fingers 38a and 38b which are capable of limited rocking movement around the upper end of the spring as a center.

The under side of the lay at the left end as viewed in Fig. 2 has secured thereto a pair of brackets 46 and 47 on which are mounted for rotation, respectively, sheaves 48 and 49. A cable 50 is attached to the end 44 of the equalizer 39 by means of a connector 51 having spaced fingers 51a and 51b capable of moving around the end 44 of cable 39 as a center. One portion of said cable 50 extends from the hook eye 51 around the sheave 49 and is attached to a pin 52 carried by a small bracket 53 secured to the backstay 13. The other side of the strand 50 extends around sheave 48 and is connected to another pin 52 in another bracket 53 also rigid with respect to the backstay.

In like manner on the right end of the lay as viewed in Fig. 2 a second cable 54 has connection with the end 45 of cable 39 by means of a connector 55 having fingers 55a and 55b to engage cable 54 at two spaced points. One side of said cable 54 passes around sheave 56 mounted in bracket 57 on the under side of the lay and is attached to a reed pin 52. The other side of cable 54 passes around sheave 58 mounted for rotation in a fourth bracket 59 on the under side of the lay and is connected by means of the fourth pin 52 to the backstay. The pins 52 and their brackets 53 are all substantially the same, as indicated in Fig. 1. It is to be understood that the strands 50 and 54 are capable of sliding movement through hook eyes 51 and 55, respectively, in the same manner in which the equalizer 39 is capable of slipping through the hook 38.

Under normal conditions as the lay approaches front center the reed will engage the filling to be beaten into the cloth and any yielding which is rendered necessary during this operation will be permitted by the single spring 36 acting through the ends of the cables 50 and 54 attached to the several pins 52. Should the let-off hesitate in its motion

and create excess tension in the warp threads the reed will encounter abnormally high resistance but this will be evenly distributed because of the fact that the cables 50 and 54 are capable of slipping through their respective hooks and also strand 39 is free to slide through its hook 38. Also, if it be desired to increase the resistance offered by the reed when a heavier grade of cloth is being woven the winged nut 37 may be operated to lower the eye 32, thereby increasing the pull which is exerted by the spring 36 on the several pins 52.

Having thus described my invention it will be seen that changes and modifications may be made therein by those skilled in the art without departing from the spirit and scope of the invention and I do not wish to be limited to the details herein disclosed, but what I claim is:

1. In a lay for a loom, a reed movable with respect to the lay, a single resilient element, and means acting in tension to operatively connect said element to the reed at a plurality of different points along the length of the reed, said element acting through said means to offer equal degrees of resistance to movement of the reed with regard to the lay at all of the points.

2. In a lay for a loom, a reed movable with respect to the lay, a single resilient element, a flexible device connected operatively to the reed at a plurality of points along the length of the reed, and means to connect said device operatively to the single resilient element to cause said element to offer resistance to the movement of the reed with respect to the lay at each of the points of operative engagement between said reed and the flexible device.

3. In a lay for a loom, a reed movable with respect to the lay, a single resilient element, a plurality of connected flexible members one of which is operatively connected to the resilient element and the other of which is operatively connected to the reed at a plurality of points along the length thereof to offer resistance to relative movement of the reed with respect to the lay by a force derived from the said resilient element.

4. In a lay for a loom, a reed movable with respect to the lay, a single resilient element, a system of flexible devices connected to the reed at a plurality of points along the length thereof, and means to connect said devices to the resilient element, the latter offering resistance through each of the devices to movement of the reed with respect to the lay.

5. In a lay for a loom, a reed movable with respect to the lay, a single resilient element, a flexible device operatively connected to the reed at a plurality of points along the length of the latter, and an equalizer interposed between said device and the resilient element, the latter acting by a force transmitted through and distributed by the equalizer to

offer substantially the same resistance to relative movement of the reed with respect to the lay at each of the points where the flexible device is operatively connected to the reed.

5 6. In a lay for a loom, a reed movable with respect to the lay, a single resilient element, a pair of flexible members each operatively connected to the reed at a plurality of points along the length of the same, and an equalizer operatively connecting said flexible members with the resilient element and acting to transmit force from the resilient element to the reed at the points where the latter has operative connection with the flexible members,

10 15 20 25 7. In a lay for a loom, a reed movable with respect to the lay, a single resilient element, and an equalizer operatively connected to the lay at a plurality of points and located intermediate the ends of the reed and connected to the resilient element, the latter acting through the equalizer to yieldingly resist movement of the reed with respect to the lay at each of said points.

8. In a loom lay having a lay sword, a single resilient element mounted on the sword, and a flexible equalizing device operatively connected to the resilient element and the reed to offer substantially the same yielding resistance to relative movement of the reed with respect to the lay at a plurality of points along the length of the reed.

30 35 40 45 9. In a loom lay having a reed movable with respect to the lay and having also a lay sword, a single spring supported by the lay sword, and an equalizer interposed between the spring and a plurality of spaced points along the length of the reed, said equalizer offering yielding resistance in substantially equal amounts at said points to movement of the reed with respect to the lay.

10. In a loom lay having a reed movable with respect thereto, a resilient element, an equalizer interposed between the resilient element and a plurality of spaced points along the length of the reed, said equalizer transmitting the yielding force of the spring and resisting movement of the reed at the said points with respect to the lay by forces which are substantially the same for all of said points.

11. In a loom lay having a reed movable with respect to the lay, a single resilient device, and means acting in tension and interposed between said device and the reed at a plurality of points along the length of the reed to offer substantially the same resistance to the movement of said reed with respect to the lay at all of the said points.

12. In a loom lay having a reed movable with respect thereto, a single resilient device,

sheaves mounted on the lay for rotation with respect to the latter, a flexible element movable around said sheaves and having operative engagement with the reed at a plurality of points, and an equalizer interposed between said flexible element and the resilient device and transmitting a yielding resistance offered by the device to the element and insuring substantially the same resistance being offered to the relative movement of the reed with respect to the lay at all of said points.

13. In a loom lay having a reed movable with respect thereto, a single resilient device, and equalizer means to operatively connect said device to the reed at a plurality of points along the length of said reed and to insure the transmission of resisting forces of substantially the same magnitude from said device to all of said points.

14. In a loom lay having a reed movable with respect thereto, a single resilient device, and equalizing means to connect said device operatively to a plurality of spaced points along the length of the reed, whereby said single resilient device offers uniform resistance to movement of the reed with respect to the lay at a plurality of points along the length of the reed.

15. In a loom having a lay with a reed movable with respect thereto, a single resilient element, a pair of separate devices one connected to one portion of the reed and the other connected to another portion of the reed, and an equalizer interposed between said device and the element and effective to cause said element to offer equal degrees of resistance to movement of the various points of the reed with respect to the lay.

In testimony whereof I have hereunto affixed my signature.

ELBRIDGE R. HOLMES.
